(57) **CLAIM**

The ornamental design for language translator glasses as shown and described.

DESCRIPTION

FIG. 1 is a front view of language translator glasses showing my new design;

FIG. 2 is a rear view of the language translator glasses;

FIG. 3 is a right side view of the language translator glasses;

FIG. 4 is a left side view of the language translator glasses;

FIG. 5 is a top view of the language translator glasses;

FIG. 6 is a bottom view of the language translator glasses; and,

FIG. 7 is a top front side perspective view of the language translator glasses.

The broken lines in FIG. 6 depict portions of the article and form no part of the claimed design. The broken lines in FIG. 2 depict boundaries of the claimed design and form no part thereof.
